BOTTLE CRATE

John F. Maurer, Jr., North Bergen, N. J.

Application April 7, 1937, Serial No. 135,460

3 Claims. (Cl. 217—35)

This invention relates to bottle crates and while not necessarily restricted thereto the same is especially directed to an improved element for milk bottle crates which element serves in the dual capacity of an inner supporting shelf and a cushioned partitioning means for the bottles.

At the present time, it is customary to provide the bottles with stenciled lettering and other indicia which is susceptible to obliteration or marring as a result of scratching of the bottle surfaces on rough or hard partition elements, and it is therefore an aim of this invention to provide a bottle partitioning means including contact portions of a soft, yieldable, resilient material which, in addition to preventing scratching of the bottle surfaces which contact therewith, reduces to a marked degree the noise incident to the clashing of the bottles with metallic partition surfaces.

It is also common practice recently to utilize what is known as "snow ice" as a cooling medium for maintaining the contents of the bottles at a safe temperature during transportation and delivery, and it is therefore essential to provide a support for this type of cooling medium which approximately fills the spaces between the bottles so as to retain said medium in place.

More particularly the invention comprehends a combined ice supporting shelf and bottle partitioning member which is fashioned from sheet metal or an equivalent material provided with bottle receiving openings approximating the size and shape of the bottles with vertically slotted fingers depending from and circumferentially spaced about said openings, together with means for connecting in spaced opposed relation the mating fingers of adjacent openings so as to define mountings for substantially cylindrical resilient contact elements, the opposite portions of which protrude through the slots and extend radially inward beyond the peripheries of the openings.

As a further feature the invention resides in a bottle crate unit of the indicated character which is so fashioned and emplaced as to permit of the use of relatively thin, light-weight material possessing requisite strength to withstand the usage to which it is subjected.

With the above enumerated and other objects in view, the invention is set forth in greater detail in the following specification, illustrated in the accompanying drawings in which several forms thereof are disclosed, while the claims cover variations and modifications which fall within the scope of the invention.

In the drawings:

Fig. 1 is a top plan view of a milk bottle crate equipped with an ice supporting shelf and bottle partitioning member constructed in accordance with the invention, parts of the crate being broken away and shown in section to disclose the features of construction of the device.

Fig. 2 is a fragmentary transverse sectional view on a relatively larger scale and on a plane designated by the line 2—2 of Fig. 1.

Fig. 3 is a fragmentary sectional view taken approximately on the line 3—3 of Fig. 1.

Fig. 4 is a detail sectional view taken approximately on the line 4—4 of Fig. 3.

Fig. 5 is a transverse sectional view similar to Fig. 2 and 3 through an ice supporting shelf and bottle partitioning member illustrating a modification of the invention.

Fig. 6 is a bottom plan view of one of the fingers.

Fig. 7 is a detail sectional view taken approximately on the line 7—7 of Fig. 5.

Referring to the drawings by characters of reference, 10 and 11 designate respectively the vertical side and end walls of the crate structure which are preferably of wood and either of single panel or a slatted construction as shown, and said walls are provided on their inner surfaces with grooves 12 to receive the marginal edges of the combined ice supporting shelf and bottle partitioning member designated generally by the reference character 13 which constitutes the present invention and which is constructed as a unit for incorporation in the crate structure.

Preferably the unit is fashioned from sheet metal, such as galvanized iron, which is cut, bent and formed by suitable dies to provide rows of bottle receiving openings 14 approximating the size and shape of the bottles. In order to render the unit 13 sufficiently rigid against bending without the necessity of utilizing sheet material of too great a weight, longitudinal and transverse beads 15 and 16 are formed which extend between adjacent openings, the beads preferably terminating in spaced relation to the marginal edges. The unit is further strengthened by downturned flanges 17 at the outer marginal edges and by annular downturned flanges 18 surrounding the bottle receiving openings 14.

In order to center the bottles in the openings 14 and to maintain them in spaced relation to and out of contact with the walls of the openings 14, while preventing contact of the bottle surfaces therewith and scratching of the same when emplacing or removing the bottles from the

crate, soft yieldable resilient contact elements 19 are circumferentially distributed about the openings with their peripheries extending radially inward beyond the peripheries of the openings. The contact elements are preferably of rubber or any equivalent soft yieldable resilient material and are preferably, as shown, of cylindrical formation, hollow or tubular elements being shown in the present instance although, obviously, they may be solid or of a different shape within the scope of the invention.

The elements 19 are supported in juxtaposition to the openings by means of mating pairs of fingers 20 which are preferably integral with the unit 13 and bent downwardly therefrom and formed from the material cut from adjacent openings 14. As shown, the fingers 20 are provided with vertical slots 21 of slightly greater length than the length of the elements 19 and of slightly lesser width than the diameter of the elements 19. Suitable means is provided for connecting in spaced opposed relation the mating fingers of adjacent openings and as herein disclosed this is accomplished by forming the opposite side edges of the fingers with flanges 22 which abut with the corresponding flanges of the mating finger. The lower ends of the fingers are offset inwardly as at 23 towards each other and are suitably secured together. As illustrated, clips 24 are provided for securing the lower ends of the fingers against separation and the connecting or bight portion 25 of the clips provides a supporting surface for the lower end of each element 19. The elements 19 are preferably capable of rotation within the fingers so as to present new contact surfaces for increasing the length of life of the contact elements.

In the modified form of the invention illustrated in Figs. 5, 6 and 7, the unit 30 constituting the bottle partitioning member and ice supporting shelf is of the same general construction as that disclosed in the first form of the invention but in this instance the soft yieldable resilient contact elements 31 which are of tubular formation are supported in juxtaposition to the bottle receiving openings of the unit by contractive engagement about the mating pairs of fingers 32 which are preferably integral with the unit and bent downwardly therefrom and formed from the material cut from adjacent openings. As shown in this instance, the lower extremities of the fingers are provided with T-shaped heads 33 which retain the elements 31 in place against unintentional axial displacement. The radial portions of the fingers are formed with longitudinally extending ribs 34 which are directed towards each other while the outer edges are provided with inwardly directed abutting flanges 35 making for a rigid construction.

What is claimed is:

1. A combined ice supporting shelf and bottle partitioning member for bottle crates, comprising a single unitary panel of sheet material, cut, bent and formed to provide a plurality of bottle receiving openings, vertically slotted fingers depending from and circumferentially spaced about said openings with adjacent fingers of adjacent openings disposed in parallel mating relation, means at the opposite edges of said mating fingers for spacing the same from each other, means for connecting the fingers at their lower ends, and cylindrical resilient elements of greater diameter than the width of the slots and the spacing of the mating fingers mounted between said mating fingers with diametrically opposite portions thereof protruding through the slotted portions of the fingers and extending inwardly beyond the edges of the openings.

2. A combined ice supporting shelf and bottle partitioning member for bottle crates, comprising a single unitary panel of sheet material cut, bent and formed to provide a plurality of bottle receiving openings, vertically slotted fingers depending from and circumferentially spaced about said openings with adjacent fingers of adjacent openings disposed in parallel mating relation, means at the opposite edges of said mating fingers for spacing the same from each other, means for connecting the fingers at their lower ends, and tubular cylindrical resilient elements of greater diameter than the width of the finger slots and the spacing of the mating fingers mounted for rotation between the mating fingers with diametrically opposite portions thereof protruding through the slotted portions of the fingers and extending inwardly beyond the edges of the openings.

3. A combined ice supporting shelf and bottle partitioning member for bottle crates, comprising a single unitary panel of sheet material cut, bent and formed to provide a plurality of bottle receiving openings, vertically slotted fingers depending from and circumferentially spaced about said openings with adjacent fingers of adjacent openings disposed in parallel mating relation, means for spacing said mating fingers from each other, means for connecting the fingers at their lower ends, and resilient elements of greater cross sectional size than the width of the slots and the spacing of the mating fingers and mounted between the mating fingers with opposite portions thereof protruding through the slotted portions of the fingers and extending inwardly beyond the edges of the openings.

JOHN F. MAURER, JR.
